APPLIANCE FOR REMOVING NAIL POLISH
Eugène Jim Politzer, 65 Rue Jouffroy, Paris, France
Filed Dec. 3, 1962, Ser. No. 241,851
Claims priority, application France, Dec. 7, 1961,
881,290, Patent 1,316,540
1 Claim. (Cl. 132—74.5)

Up till now, for removing worn or soiled polish from the finger-nails, the user dipped a cotton wool pad or rag in solvent, holding this wad or rag in one hand, and rubbing the nails of the other hand.

This method has numerous disadvantages. In the first place, the opened bottle risks upsetting; then an appreciable quantity of liquid is necessary for soaking the wad or rag, which leads to waste, seeing that this wad or rag is thrown away after being used. On the other hand, the polish of the nails of the hand holding the wad is attacked and damaged by the solvent, which makes it necessary to remove the polish from all the nails, in turn. It is thus very difficult individually to remove the polish from a given nail.

For this reason, the user is generally obliged to proceed to remove the polish from all of the nails, and to make a fresh general application of the polish, even if, in fact, the polish on a single nail is damaged and requires to be renewed.

The present invention obviates these disadvantages by creating an appliance that easily allows the polish to be removed from a single nail individually, without affecting the other finger-nails, both of the treated hand as well as the hand holding the appliance. This appliance thus enables only the finger-nail requiring it, to be treated, and only to consume the quantity of polish solvent that is absolutely necessary for the work to be carried out, affording in this manner a great saving in time and money. The appliance can be carried when travelling without any risk of its being upset in toilet sets and other luggage.

According to the invention, the appliance comprises a receptacle containing the solvent having a pad or brush in its neck and at least one rigid component against which the working end of the pad or brush can bear, thus enabling the user holding the appliance in one hand, vigorously to brush each nail of the other hand separately.

According to various embodiments of the invention, the bearing component is formed by a bevel or oblique surface of the neck of the receptacle and a stopper inserted in this neck, or else by a support held by a stopper and engaged inside of the pad or brush used for applying the solvent. The passage of the solvent contained in the receptacle to the pad or brush for applying can be effected by capillarity in following the pad or brush or a wick that can go down to the bottom of the receptacle or else by a straight tube passing through the stopper or pad.

Various other characteristics of the invention will moreover be revealed by the detailed description which follows of the forms of embodiment given by way of examples that are not restrictive and are shown in the attached drawing.

FIGURE 1 is a vertical section of the appliance.

FIGURE 2 is a front elevation of the appliance, partly

2

in section, along a plane perpendicular to that of FIGURE 1.

FIGURE 3 is an elevation-section of a second form of embodiment.

FIGURE 4 is a partial elevation-section of a third form of embodiment.

FIGURE 5 is an elevation-section of a fourth form of embodiment.

The appliance of FIGURE 1 is essentially formed by a flask 1, preferably of compressible synthetic material, having a neck 3 in which a stopper 4 is placed drilled with a bore 5 accommodating a wick 6 and a straight tube 7. The straight tube 7, which passes downwardly through stopper 4 and extends to the vicinity of the bottom of flask 1, has for its function to conduct the solvent 10 to the upper part of the wick 6 by gravity, so that the solvent may be applied onto the nails. The stopper 4 has a bevel 8 at its top part. 9 denotes a closing cap having a tapped base screwing on to the neck 3 of the flask.

When the flask is filled with solvent for nail polish 10, the user can, by holding the flask in one hand, firmly apply the end 6 of the wick forming a pad to the finger-nail from which the polish is required to be removed, 25 for this end of the wick presses on the bevel 8 which firmly holds it.

According to an alternative (not shown), the stopper 4 can be moulded with the neck 3 of the flask, these two elements forming one piece. Likewise, according to 30 another alternative, the neck 3 of the flask is extended upwards and cut with a bevel, the pad being forcibly inserted in this neck. In this case, it is the actual extension of the neck cut in a bevel that forms the oblique bearing surface 8 against which the end of the pad 35 coming out of the flask bears for enabling the user vigorously to rub her finger-nails.

According to the alternative of FIGURE 3, the flask 11 comprises a stopper 14 drilled with a bore 15 in which a wick 16 is inserted having a part 16' descending to 40 the bottom of the flask and a projecting part 16'' emerging on the bevel 18 against which it presses during the operation of removing the nail polish.

19 denotes the removable cap. In this case, the solvent rises by capillarity through the wick, the appliance 45 not comprising the rising tube as in FIGURE 1.

In the alternative of FIGURE 4, the flask 21 with a threaded neck 23 accommodating the cap 29 is provided with a stopper 24 in which a pad 26 passes through a bore 23A. The stopper 24 also has a bevel 28 against 50 which the working part of the pad 26 presses. In the non-utilization position shown in FIGURE 4, the stopper is turned round so that the applying part of the pad 26 is bathed in the liquid 30 and is thus cleaned. To utilize the appliance, the stopper 24 is turned round by inserting 55 its part 24' in the neck of the flask, so that its working end is placed in the position 26' shown in dotted lines, by pressing against the bevel 28' to remove the polish.

FIGURE 5 shows another embodiment in which the flask 31 with a threaded neck 33 accommodates the 60 closing cap 39. A stopper 34 inserted in the neck of the flask has a bore 35 accommodating a tube 32 having a bore 32' and with a splayed-out head 32''. The pad 36 is threaded on to the top part of the tube and in a widened part 35' of the bore of the stopper 34. The 65 tube 32 acts not only for the passage of the solvent

inside the flask towards the pad 36 which it soaks, but also as a support or rigidifying rod so that when the user holding the flask 31 in one hand, vigorously presses the pad on the finger-nails of the other hand to remove their polish, this pad is held by its support against the rigid tube 32.

The wicks, pad and internal packing mentioned can be of any suitable material, more particularly of felt, foam rubber or synthetic materials, etc. The wick and pad could also be replaced by tufts of bristles forming a brush or dense pencil and which would bear on the rigidifying elements provided, these latter being able to assume very varied shapes, without going outside of the scope of the invention. The wick, pad and internal packing can be provided removable and to be changed at will.

The flask can be of any other suitable material and can also have various shapes.

I claim:

An appliance for removing the polish from fingernails, comprising a compressible receptacle having an open-neck portion of reduced size at the upper end thereof, nail polish solvent within said receptacle in free state, a hollow plug disposed within said neck portion, said plug having an inclined surface at its upper end thereof, said inclined surface being flat along its entire length, an absorbing means mounted in said plug and extending above said plug so that upon deformation said absorbing means will bear against said flat inclined surface, said absorbing means also extending into said receptacle to fill only a small portion of said receptacle so that the

10

15

25

30

solvent within said receptacle is mostly in free state, and a hollow tube disposed beside said absorbing means in said hollow plug, the lower end thereof extending into said solvent, the upper end of said tube lying adjacent said inclined surface so that—upon deformation of said absorbing means—said absorbing means bears against the upper open end of said tube and said inclined surface, said tube acting to conduct the solvent to the upper end of said absorbing means.
